Samuel H. Gibbs, of Albany, New York
 assignor to
 A. H. McArthur & Co. of Hudson, N.Y.
 Letters Patent, No. 852, Dated Dec. 9th 1856.

The Schedule referred to in these Letters Patent and
 making part of the same.

Be it known that I, Samuel H. Gibbs, of the City of Albany, State of New York, have produced a new and original ornamental design for the plates of an Elevated Oven Cooking Stove and I hereby declare that the annexed drawings, forming part of this Specification, are full and accurate delineations of the said plates with their ornamental parts, the duplicate plates not represented, and forming parts of the stove corresponding with those represented, being symmetrically similar to them.

What I claim as my production and desire to secure by Letters Patent is the combination and arrangement of ornamental figures and forms represented in the accompanying drawings forming together the ornamental design for the plates of an Elevated Oven Cooking stove.
